UNITED STATES PATENT OFFICE.

KENNETH L. CURTIS, OF NEW YORK, N. Y.

REFRIGERATING APPARATUS.

Application filed August 12, 1922. Serial No. 581,304.

To all whom it may concern:

Be it known that I, KENNETH L. CURTIS, a citizen of the United States, and resident of the city of New York, borough of Manhattan, county and State of New York, have invented certain new and useful Improvements in Refrigerating Apparatus, of which the following is a specification.

This invention relates to refrigerating apparatus.

An object of the invention is the provision of an improved and simplified refrigerating apparatus which is particularly adapted for maintaining a refrigerator or cooler intended for containing foods or liquid, etc., at a suitable temperature. The apparatus is one by means of which a suitable liquid refrigerant—water being preferred—is placed in a closed chamber and evaporated therefrom, the chamber in the preferred embodiment of the invention being located within the space to be refrigerated, and the refrigerant being evaporated in such manner as to constantly maintain the desired low temperature in the refrigerator. Apparatus embodying the invention, due to its automatic and reliable operation, is especially useful for family refrigerators.

This application is in part a continuation of my copending application Serial No. 539,881, filed February 28, 1922, for process and apparatus for refrigeration.

According to the preferred embodiment of the invention as hereinafter described, a relatively high vacuum is maintained in the refrigerant chamber, sufficient to readily evaporate the water at a rate that will maintain the refrigerant at a low temperature somewhat above the freezing point, and this without driving the vacuum pump at too high a speed. The water in the refrigerant chamber is maintained at a substantially constant level, and the air in the refrigerator is caused to circulate by passing upwardly and thence through openings traversing the refrigerant chamber in the upper part of the refrigerator, from which upper part the air again descends.

The invention consists in the novel features, arrangements, construction and combinations of parts hereinafter described according to the preferred embodiment thereof, and the invention will be more particularly pointed out in the appended claims.

Further objects and advantages of the invention will more fully appear from the

following description taken in connection with the accompanying drawings illustrating by way of example the present preferred embodiment and two modifications of apparatus comprising the invention, and in which—

Fig. 1 represents a somewhat diagrammatic view, partly in side elevation and partly in section, of the entire apparatus;

Fig. 2 is an enlarged section taken on lines 2—2 of Fig. 1, illustrating the vacuum pumping apparatus at one point in its operation;

Fig. 3 is a sectional view similar to that shown in Fig. 2, illustrating the vacuum pumping apparatus at another point in its operation;

Fig. 4 is a section taken on line 4—4 of Fig. 3;

Fig. 5 is a partial enlarged sectional view corresponding to the upper part of Fig. 2;

Fig. 6 is a partial enlarged sectional view corresponding to the upper part of Fig. 3;

Figs. 7, 8 and 9 show modifications of the refrigerator.

In accordance with the invention, a liquid refrigerating medium, preferably water, is fed into a chamber which is located in a space to be cooled. I have illustrated a closed chamber, or container, 1, located within a refrigerator 2 adapted for containing food, etc., as in the usual domestic ice box, or refrigerator. The container 1 is preferably located within the refrigerator near the upper portion of the interior thereof, and may be supported by suitable supports 3, 3, which are preferably spaced inwardly somewhat from the outer walls of the refrigerator. The liquid refrigerating medium, preferably water, as stated, is fed into the chamber 1 by a pipe 4. Means must be provided for maintaining the supply of liquid to chamber 1 to compensate for vapors which are withdrawn therefrom during the refrigerating process. Preferably the water or liquid level is maintained at a constant desired level, as illustrated for example at 5, by means of a float valve, the valve 6 being illustrated as pivoted to the wall of container 1 and having an arm 7 carrying a float 8 secured thereto, the valve 6 closing when the liquid reaches the desired level and opening when the level falls, in the well known manner.

A continuously driven suction pump is

connected by pipe 9 to the interior of container 1. A partial vacuum is maintained in chamber 1 by the operation of this pump which causes the refrigerating medium to 5 evaporate and thus to give up heat, the amount of heat removed being practically proportional to the amount of vapor removed from chamber 1. When water is used as the refrigerating medium, as is preferred, no provision need be made for 10 condensing and using the same again. It also may be noted that the thermostat and pressure control devices which are essential to the successful operation of various automatic refrigerating apparatus now in use, are not 15 needed.

The chamber 1 is preferably provided with a plurality of pipes 10 extending therethrough and opening at both ends into the 20 space to be refrigerated. The members 3 which serve as supports for chamber 1 also preferably serve as partitions extending from side to side of the refrigerator with openings 11 at the bottom thereof, so that 25 when the device is in operation the warmer air will pass upwardly through the space between partitions 3 and the outer walls, pass downwardly through the pipes or passages 10 when the heat is abstracted, and 30 through the holes in shelves 12 and openings 11, the air then again passing up along the outside passages. The refrigerator may be provided with perforated shelves 12 in the usual manner.

35 The vacuum pumping apparatus is shown as contained within the cylinder 13 and the crank case 14. The vacuum producing or suction apparatus is of improved or novel design, constituting one of the features of 40 the invention, and is particularly well adapted to produce an exceedingly low vacuum in chamber 1, which is necessary for or highly desirable in the operation of the system.

45 The vacuum pump which is preferably used combines a zero-clearance outlet valve and a mechanically operated inlet valve. The zero-clearance is obtained by making the outlet valve extend over the full diameter of the cylinder so that the piston may 50 move to the extreme end of the cylinder or even over-travel without doing any damage. The inlet valve preferably takes the form of a sleeve which seals the inlet opening by 55 seating at its end in the manner of a poppet valve and not by sliding over a port to entirely cover or uncover the same, as is customary with sleeve valves. By the use of a mechanically operated inlet valve and an 60 outlet valve of the character referred to I am able to obtain great efficiency and may produce an exceedingly low vacuum. By a mechanically operated inlet valve I mean one which operates by mechanical means, inde- 65 pendently of any difference of pressure on

the opposite sides of the same, so that operation of the same will be certain even when operating under conditions of such extreme vacuum, that there would not be enough pressure on either side of a valve to open the 70 same at any time.

In the preferred form of the apparatus, as illustrated, the vacuum pump apparatus comprises a pair of cylinders 13 and 15 which are secured to an air-tight crank case 75 14, the cylinder 13 being shown as mounted on the upper end of the crank case, with its lower end opening into the same, while the cylinder 15 is mounted within the lower portion of the crank case. The pistons of the 80 two cylinders are connected to operate in unison, the piston 16 of the upper cylinder serving to draw water vapor, or generally speaking, the vapor of the liquid refrigerant, from chamber 1 in the refrigerator and to 85 discharge the contents of the crank case through pipe connection 18 into a suitable receptacle 19. The two cylinders are preferably the same in their construction, except that the lower is much smaller than 90 the upper one.

The exhaust valves 20 and 21 of the cylinders 13 and 15 are preferably both of the full diameters of the cylinders and may be considered as movable cylinder heads. They 95 are held in place by springs 22 in the case of the upper cylinder, and 23 in the case of the lower cylinder, and are opened, at the end of each outward piston stroke, by the pressure of the exhaust gases or vapor, or 100 condensed liquid in the case of the lower cylinder, during the regular operation of the chamber.

The inlet valves both preferably take the form of sleeves as shown, the sleeve valve of the upper cylinder 13 being indicated at 24 and the sleeve valve of the lower cylinder being shown at 25. These sleeves surround the pistons and form in effect the cylinder walls. The upper sleeve 24 is preferably 105 provided with an inclined surface 26 at its upper end which is adapted to seat against a correspondingly shaped surface 27 on the valve seat 28, while the lower sleeve 25 is provided with a similarly shaped lower end 110 surface 29 which seats against a similar seating surface on the seat 30. The sleeves are 115 preferably moved in one direction by a cam or similar mechanical device, and in the other direction by spring action.

In the preferred form of the device, as illustrated, the two cylinders 13 and 15 are diametrically opposed to each other and the two pistons are operated in unison from the same wrist pin. As illustrated, the two 125 pistons may be connected together by a rod 31 in axial alignment with both of the same, a connecting rod 32 being pivotally connected at its upper end to a pin 33 on piston rod 31 while the lower end of the connecting rod 130

is pivotally connected to the pin 34 on a disk 35 secured to the shaft 36 which is constantly rotated from a suitable motor or power device.

5 The two sleeves 24 and 25 are connected together, as by clamping members 37 and 38 secured respectively to the lower end of the upper sleeve and the upper end of the lower sleeve, these clamps being secured together 10 by rods 39 extending between the same (see Fig. 4). Disk 35 is preferably formed as a cam or eccentric, a roller 40 resting against the outer surface thereof. Preferably roller 40 is carried by an arm 41 having down- 15 wardly extending portion 44 above the cam disk 35, arm 41 being pivotally secured at its outer end, at 42 to the crank case. The cam disk and roller 40 are utilized for moving the sleeve valves in one direction, while 20 springs are used for moving the sleeves in the other direction, suitable springs being indicated at 43 secured at their opposite ends to the clamping member 38 and the cylinder 15.

25 A push rod 45 for actuating the sleeve valves rests on or is secured to the upper portion of arm 41. Preferably push rod 45 is formed as a tube, for a purpose to be explained hereafter, this tube extending 30 through a suitable opening in the clamping member 37, through an aligned opening in the top member 46 of the crank case and into an aligned bore or passage 47 formed in cylinder 13, in which it is guided.

35 Preferably push rod 45 operates the sleeve valves through a spring 48 (see Figs. 2 and 3) which must be sufficiently stiff to move the sleeves against the pull of springs 43 and yet be capable of being compressed by a slight 40 over-travel of push rod 45 itself, so as to prevent possible damage of the parts in case the push rod tends to over-travel slightly for any reason. Spring 48 may surround the rod or tubular member 45 between a cup 45 or abutment 49 secured to the rod, at one end, and a cup 50 at the other end which bears against the clamping member 37. Accordingly, both sleeves will be moved upwardly by cam 35 and will be moved downwardly by springs 43 as soon as such movement is permitted by cam 35 during each operation of the pistons.

45 In the operation of the device as so far described, the pipe connection 9 which leads 55 to the evaporating chamber 1 in the refrigerator, is connected through the opening 51 in the upper head of cylinder 13 with a passage 52 which leads into the interior of cylinder 13, above piston 16, when sleeve 24 60 is away from its seat 27, as shown in Fig. 6.

In the regular operation of the system, air and water vapor, or other gases, will be sucked into the space above piston 16 on the descending stroke of the latter, as shown in 65 Figs. 3 and 6, inlet valve 24 then being

opened and outlet valve 20 closed. Valve 24 will be moved upwardly against its seat about the time that piston 16 starts on its return or upward movement so that outlet valve 20 will be moved from its seat against 70 the pressure of springs 22 and the contents of the cylinder above the piston will be forced into passage 47 previously referred to. The gases pass from passage 47 into the tubular member 45 which extends into the 75 lower end of the same and pass out through an opening 53 in member 45 into the interior of the air-tight crank case.

Piston 17 of the lower cylinder will be rising on its intake stroke as the upper piston is moving upwardly on its expelling stroke. Condensed water, or air and gases in the crank case, and surplus oil will pass through an opening 54 which extends through cylinder 15 of the lower pump 80 member into an annular space 55 formed in the cylinder 15 surrounding sleeve 25. The sleeve being raised from its seat, as shown in Fig. 2, this material will be drawn into the interior of the cylinder, and when sleeve 85 90 valve 25 closes and piston 17 descends, the outlet valve 21 will open and this material will be forced out through pipe 18 into the container 19 shown in Fig. 1.

It will be noted that the outlet valves 20 and 21 of the two cylinders extend across the entire diameter of the cylinders and constitute what may be termed zero-clearance outlet valves, since the pistons may travel on their exhaust strokes to the full end of 100 the cylinders, or may even over-travel. Valves 20 and 21 may be considered as movable cylinder heads.

The pump pistons are designed to operate at high speed in the system described, and considerable power would be required if the upper piston had to operate at this speed to withdraw air from chamber 1 at the beginning of the operation, when the entire system is filled with air at atmospheric pressure. Also the air thus drawn from the evaporating chamber 1 by the large upper cylinder and discharged into the crank case would be more than the smaller lower cylinder could remove in time to prevent the building up of a high pressure in the crank case, which would further increase the power required. Accordingly, in the preferred form of the invention the lower cylinder alone is utilized at the beginning of the 110 operation, the lower cylinder then withdrawing air from the interior of the crank case and through connection 47 and a bypass connection 56 from the container 1. Pump cylinder 15 is considerably smaller in 120 diameter than the upper pump cylinder and very little power is required to operate the same even with the entire apparatus full of air. Automatic means are provided, in the preferred form of the invention, to become 125

130

effective when a sufficient vacuum has been established in the system, to cut in the upper cylinder so that from this time on the larger capacity upper cylinder will be effective for maintaining vacuum and evaporating the water gases from chamber 1, the lower chamber serving from this time on merely to remove the air or gas, oil and condensed liquid from the crank case.

- 10 In the form of construction described bypass 56 extends from the inlet opening 51 through a valve opening 56', 57, into the space 58 at the upper end of the cylinder in which the outlet valve 20 is seated, this space 15 58 opening into the passage 47 which leads to the crank case. A valve 59 is positioned to seal the opening 56' extending from the horizontal portion of bypass 56 into the recess 57, when a sufficient vacuum has been 20 established in the system, so as to shut off the bypass.

This valve 59 rests on a pile of air-tight containers 60 (Figs. 5 and 6) which rests on a support 61 which extends across the 25 construction within space 58. Containers 60 are thin hollow members, of what may be termed pill box construction, preferably formed of very thin metal. They are filled with air at atmospheric pressure, and will 30 lie flat on each other on support 61 when the pressure surrounding them in space 58 and bypass 56 is atmospheric, in which case an opening will be provided over and around the containers, as is shown in Fig. 5. When 35 this condition exists the lower pump cylinder will draw directly through passage 47 and bypass 56, from chamber 1, and the upper pump cylinder will be inoperative. After the lower pump has operated sufficiently to reduce the pressure in the crank 40 case, containers 60 will expand because of the unbalanced pressure of the air confined inside the same, and valve 59 will be lifted and held against its seat at the top of space 45 57, as is shown in Fig. 6, whereby the bypass 56 will be closed and the upper pump cylinder rendered effective.

In the preferred construction of apparatus the wrist pin 33 is preferably mounted 50 between ball bearings 62 and the crank pin is similarly provided with ball bearings (not shown). The crank shaft 36 is preferably provided with a step bearing 63 to take the thrust caused by the vacuum in the 55 crank case, the step bearing forming a seal and preventing air from leaking into the crank case at this point. Oil may be supplied to the face of this step bearing through pipe 64, the oil being slowly sucked into the 60 crank case along the surface of the crank shaft 36 and thereby lubricating the crank shaft.

The remaining parts of the pumping apparatus are preferably lubricated by a single 65 oil supply pipe 65, indicated in Figs. 1 and

4, which supplies oil to an annular recess 66 located between the upper cylinder sleeve 24 and the cylinder casing 13. This oil is sucked upwardly into the upper space 58' surrounding sleeve 24 whence it flows over the upper edge of sleeve 24, when open, into the cylinder above the piston. Oil is also sucked down from recess 66 into the crank case, where it is splashed by the crank disk 35 so as to reach every moving part in 75 the crank case.

The receptacle 19 into which the lower cylinder 15 discharges serves as an oil reservoir and also as a separator to recover the surplus oil from the discharge of the pump. 80 The condensed water vapor from the crank case, when water is the refrigerating fluid used, settles to the bottom of vessel 19, as is indicated at 66, the oil rising above the water, as is indicated at 67. The oil is drawn upwardly from this space by pipe 65, previously referred to, and is used over again. The water is forced upwardly in a trap 68, by the weight of the oil 67 above the same in vessel 19, the water flowing out 90 through a pipe 69 in trap 68.

In Fig. 7 I have shown a modification of the invention for use in refrigerator apparatus, more correctly known as water or liquid coolers. In this apparatus the refrigerator chamber, space or container for the substance to be chilled, such for example as water, is indicated by the coil 72 which may be connected at one end to a suitable source of water, and having the outlet 73. 100 This takes the place of the refrigerator chamber or space for foods and the like, shown in the first form of the invention, and conversely to the first form of the invention, instead of the refrigerator chamber being located wholly within the refrigerator chamber in this modification, the coil 72 is located within the refrigerator chamber 1' which, as in the first case, has its outer wall 70 suitably packed with insulating material and may be provided with any suitable opening thereto (not shown) for cleaning the same. This refrigerator chamber, as in the first modification, is provided with an outlet pipe 9' to which the pumping apparatus 13 is connected, exactly as in the first modification, and the chamber is also provided with a refrigerant inlet pipe 4' connected to a suitable source of water such as a city water supply, and the level of water in the chamber is maintained by the valve 6' controlled through the float 8', all as heretofore described in connection with the first form. The method of operation, except for the differences of construction 110 pointed out, is identical to that already described in connection with the first form.

In Figs. 8 and 9 I have shown another modification of the invention wherein the refrigerator chamber consists of an inner 120

- chamber 74 preferably formed of metal and suitably spaced apart from the wall of the refrigerant chamber 1" as by suitable spacers 75, so as to provide a substantial space 5 between the chamber 74 and the outer metal wall of the chamber 1", which space constitutes the refrigerant chamber. This refrigerant chamber is provided with a suitably packed outer wall 70, and is connected with 10 the pump through the pipe 9" in the manner heretofore described, and the refrigerant level is automatically maintained as heretofore described, by the valve 6" with the float 8'. This valve 6" in this modification 15 is controlled by a pair of floats 8"-8" as shown in Fig. 9, connected through a circular member to the valve, so as to properly equalize the pressure exerted on the valve 6".
- 20 The refrigerator chamber is provided with any suitable openings such as the cover 76, suitably packed in the same manner as indicated for the walls of the refrigerant chamber.
- 25 The refrigerating apparatus described is inherently self regulating, because as the temperature of the water in chamber 1 is lowered, the water vapor withdrawn therefrom through pipe 9 becomes less dense and 30 as the amount of cooling produced in chamber 1 at a given pumping speed is directly proportional to the amount of vapor removed, it is directly proportional to the density of the vapor. For example, at 40° 35 F. temperature one pound of steam occupies 2438 cubic feet, and at 32° F. it occupies 3294 cubic feet. The removal of one pound of steam will produce practically the same amount of cooling at either temperature. 40
- 45 When a greater cooling effect is required in the refrigerator, that is, for example when food products are placed in the refrigerator which require cooling, the temperature of water chamber 1 will rise, and the vapor removed will have a greater density. The suction pump runs at constant speed and in 50 removing the vapor of greater density it removes more heat, which is the condition desired. In a like manner when the temperature of the chamber 1 falls, less heat will be removed therefrom because of the vapor removed being of lesser density. As stated, the refrigerant will not drop below the 55 freezing point because the capacity of the pump at its constant speed, is such that at the lower room temperatures which the refrigerant will encounter, there will not be sufficient evacuation to freeze the refrigerant, and at the higher temperatures the inherent property of the saturated vapor as 60 above pointed out, will operate as stated in maintaining the refrigerant temperature within the desired range. The temperature 65 of the refrigerator will accordingly be main-
- tained within a narrow range, this range being not sufficiently great to interfere with the satisfactory operation of the apparatus. As the pump runs continuously no automatic devices for starting and stopping the 70 driving motor are necessary. This is an important feature in household refrigeration because it avoids throwing heavy loads on the house circuit which would occur in starting the driving motor. Most houses are 75 equipped only with a lighting circuit with fuses of a limited capacity suitable to protect such wiring, and if motors were put on these circuits which were intermittently started without any extra precaution, the 80 result would probably be a blowing of the fuse or a dangerous heating of the circuits whenever the motor was started.
- 85 As heretofore stated, this application is in part a continuation of my co-pending application Serial No. 539,881, filed February 28, 1922, for process and apparatus for refrigeration. In this application I claim the refrigerating apparatus or refrigerating system, together with various combinations and features of the system as a refrigerating system, but I make no claim in this application to the pumping apparatus per se, since that forms the subject matter of a co-pending application Serial Number 582,128, filed 90 on August 16, 1922; nor to the method of refrigeration carried out by the system or refrigerating apparatus, since claims to the method of refrigerating constitute the subject matter of the aforesaid parent application Serial No. 539,881, filed February 28, 1922. These later applications have been filed because of requirement by the Patent Office of division among these different sets of claims in the parent application. 95
- 100 It is believed that the apparatus described and the operation of the same, as well as the method of refrigerating carried out thereby, will be readily understood from the foregoing description.
- 105 While I have described my invention in detail in connection with the present preferred embodiments thereof as shown in the drawings, it will be understood by those skilled in the art, after understanding my invention, that various changes and modifications may be made therein without departing from the spirit or scope of the invention, and I aim in the appended claims 115 to cover all such modifications as are within the purview of the invention. 120
- 110 Having thus described my invention, what I claim as new and desire to secure by Letters Patent, is:
1. In refrigerating apparatus, the combination of a refrigerating chamber, a refrigerant chamber within said refrigerating chamber and having a number of air passages therethrough for the circulation of air, 125 automatic means for maintaining the level 130

- of refrigerant in said refrigerant chamber, an air-tight crank case, a constant speed suction pump with means connecting the same to said refrigerant chamber and to said 5 crank case for pumping gases from the chamber and delivering same to the crank case, and a pump within said crank case for withdrawing gases, oil and condensed liquid therefrom.
- 10 2. In refrigerating apparatus, the combination of a refrigerating chamber, a refrigerant chamber within said refrigerating chamber and having a number of air passages therethrough for the circulation of air, 15 automatic means for maintaining the level

of refrigerant in said refrigerant chamber, a compound suction pump connected with the refrigerant chamber for sucking vapors from the refrigerant to evaporate the latter from the chamber, and means controlled 20 by pressure in the refrigerant chamber to render the pump single acting at a predetermined pressure in the refrigerant chamber whereby the pump is automatically controlled to prevent excess load thereon due to 25 compound action of the pump at high pressures.

In testimony whereof I have signed my name to this specification.

KENNETH L. CURTIS.
